[57] CLAIM

The ornamental design for a spotting telescope, as shown and described.

DESCRIPTION

FIG. 1 is a perspective view of a spotting telescope showing my new design, the pattern line on the side being partially shown for ease of illustration; FIG. 2 is a side elevational view thereof, the opposite side being identical thereto;

FIG. 3 is a top plan view, with a flexible eyecup illustrated in FIG. 2 being folded to a retracted position; FIG. 4 is a bottom plan view with the eyecup retracted; FIG. 5 is a front elevational view of an objective lens end; and

FIG. 6 is a rear elevational view of an eyepiece end with the eyecup extended.

*Fig. 1**Fig. 2**Fig. 3**Fig. 4**Fig. 5**Fig. 6*
